UNITED STATES PATENT OFFICE.

CHARLES A. JACKSON, OF BOSTON, MASSACHUSETTS.

IMPROVEMENT IN FOLDING-CHAIRS.

Specification forming part of Letters Patent No. 119,849, dated October 10, 1871.

To all whom it may concern:

Be it known that I, CHARLES A. JACKSON, of Boston, in the Commonwealth of Massachusetts, have invented a new and Improved Folding-Chair; and I do hereby declare the following to be a full and correct description of the same, reference being had to the accompanying drawing, in which—

Figure 1 is a side elevation of my chair expanded for use, and Fig. 2 is a similar elevation of the chair when folded.

The same part is marked by the same letter of reference in both figures.

In the drawing, B' marks the back supports of the chair, which are pivoted to the seat at its rear corners. The lower ends of the back rails B' are provided with pins which are received in holes in the notches A A A on the legs L. The hind legs L are pivoted to the front legs L' near B, the front corners of the seat. The front legs are hinged to the bottom of the seat, as shown.

The chair folds in such a manner that by taking hold of the back B' with one hand the chair

may be lifted with one hand and the legs L L' will drop into their proper place.

The supports B' to the back, resting upon the legs L at the points marked A A A in the drawing, form a back which may be placed at different angles.

What I claim as my invention, and desire to secure by Letters Patent, is—

The combination of the back B' of the chair with the legs L, controlling the front of the chair, and forming a back at different angles by means of the combination at the points marked A A A, and the combination at the front of the chair, marked B, by which the front legs L' are controlled and put into proper position to enable the chair to be used as a seat, all as shown and described.

The above specification of my said invention signed and witnessed at Boston this 18th day of August, A. D. 1871.

Witnesses:

C. A. JACKSON.
